UNITED STATES PATENT OFFICE.

EDMUND H. LUNKEN, OF CINCINNATI, OHIO.

WINDOW CONSTRUCTION.

SPECIFICATION forming part of Letters Patent No. 763,496, dated June 28, 1904.

Application filed January 26, 1904. Serial No. 190,728. (No model.)

To all whom it may concern:

Be it known that I, EDMUND H. LUNKEN, a citizen of the United States, residing at Cincinnati, Ohio, have invented certain new and useful Improvements in Window Constructions, of which the following is a specification.

My invention relates to windows of the general form disclosed in applications for Letters Patent of the United States filed by Bernard J. Hausfeld and myself as joint inventors September 14, 1903, No. 173,118, November 27, 1903, No. 182,860, and January 9, 1904, Nos. 188,199 and 188,200. In the type of window disclosed in said applications a secondary frame is pivotally supported in a main frame fixed in the window-opening, said secondary frame carrying a pair of sliding sashes which are balanced in suitable manner and in the case of a vertically-swinging secondary frame are interconnected by rack and pinions or associated with pinions and toothed weights, whereby a constant balancing effect is maintained for all positions of the secondary swinging frame about its pivots.

My present improvements relate to the association with the sliding sashes of the secondary swinging frame, supplemental sashes to be carried by the sliding sashes and to move as one body with the secondary swinging frame.

The invention consists in the features and combination and arrangement of parts hereinafter described, and particularly pointed out in the claims.

In the accompanying drawings, Figure 1 is a vertical sectional view through the main and secondary swinging frame with my improvement in place. Fig. 2 is a sectional perspective detail view. Fig. 3 is a sectional perspective view of a part of the sliding and hinged sashes with means for locking them together. Fig. 4 is a detail view in section of means for making a tight joint between the sliding sash and the hinged sash carried thereby. Fig. 5 is a front view of a part of a main and secondary frame with my improvement in place. Fig. 6 is a detail view. Fig. 7 is a detail view showing the connection between the sashes whereby they operate in unison.

In the drawings, 1 indicates the main frame,

which is of channeled metal and which is suitably fixed in the window-opening, and 2 indicates the metallic secondary or swinging frame, which is arranged within the main frame and swings about pivots connecting the 55 secondary frame with the main frame. These pivots are indicated generally at 3, Fig. 5, the secondary frame in this instance being arranged to swing vertically about the horizontally-disposed pivots, though it will be 60 understood that the secondary frame instead of swinging vertically may be arranged to swing horizontally, or, in other words, about vertically-disposed pivots.

My present improvements relate more particularly to the employment of a supplemental sash for each of the sliding sashes, such a combination being particularly desired in winter time to keep out the extreme cold. In carrying out my invention I combine with each 70 sliding sash a supplemental sash connected thereto, so as to move therewith in its sliding movement and also to partake of the general movement of the secondary swinging frame when the same is reversed in position to permit access to the opposite sides of the said frame and sashes carried thereby. The supplemental sashes are indicated at 4, being hinged at 5 to the sliding sashes, so as to swing 75 in a horizontal plane about vertically-disposed 80 pivots or hinges. There may be only one hinged sash for each of the sliding sashes, as shown in Fig. 5, or the said hinged sash may be formed in sections, as indicated in dotted lines in said Fig. 5, the said sections when 85 closed meeting at the central line of the sliding sash. In the present instance I have shown the hinged sash of a size to reach entirely across the sliding sash, and the hinge, as shown in Fig. 5, is located at the left-hand edge of 90 the sashes. The hinge is formed by two eyes or sleeves 6, located at the upper and lower corners of the swinging sash, and an intermediate elongated eye or sleeve 7, fixed on the side rail of the sliding sash, a hinged rod 8, 95 having a knob 9 at the top, passing through the said eyes or sleeves. When the hinged sash is formed in two sections, the same construction of hinge as just described is employed at 100 the right-hand edge, and the same construc-

tion may also be employed when but a single sash is used to reach entirely across the sliding sash, excepting that in the latter case the hinged rod 8 would of course be wanting. In 5 this instance the elongated eye or sleeve on the sliding sash would serve as a support for the eyes on the hinged sash and serve to center the hinged sash at this edge and prevent vertical play.

10 As shown in Fig. 1, packing 9^a is interposed between the hinged and sliding sash, being suitably fixed to the hinged sash. Instead of this form of packing a sheet-metal packing or weather-strip may be employed, as indicated 15 at 11 in Fig. 4, said strip being secured between parts of the hinged sash and reaching across the space between the hinged sash and sliding sash in the curved form, (indicated at 11'), so as to form a free spring portion, which 20 will accommodate itself to the space between the sashes and effectually close the same against the passage of air, dust, or other elements.

In order to hold the hinged sash in closed 25 position, I provide a lock consisting of a button or finger-piece 12, pivoted to a block 13, having a shank 14 screw-threaded into the side rail of the sliding sash. The hinged sash is provided with an opening 15 for the passage 30 of the block 13 and button 12, and when the free edge of the swinging or hinged sash has been closed against the sliding sash the button 12 projects beyond the hinged sash and may then be turned into the position 35 shown in Fig. 3 to engage the sash and hold the same in place.

In order to hold the sliding sash locked in position whether closed or slightly raised, I provide a locking-pin 16, adapted to engage 40 openings 17 in the sliding sash, the said pin being carried by a spring-arm 18, which is screwed to the bead 19 of the secondary frame. The pin has a knob 20, and by grasping this the pin may be drawn out against the pressure 45 of the spring-arm 18, and the sliding sash will then be unlocked, and when the lower opening comes opposite the pin and the same is released the lock will hold the sliding sash slightly elevated.

50 It will be seen from the above that the supplemental sash arranged as described does not interfere in any way with the use and operation of the window, as fully disclosed in the applications above mentioned, for the supplemental sash moves as one body with the sliding sashes as they are raised and lowered in their guideways, and also they move as one body with the entire secondary frame when the same is swung on the pivots to reverse the 55 same. For instance, in cleaning the windows the inner side of the lower sliding sash may be cleaned by simply swinging back the hinged sash, and of course both sides of the hinged sash are accessible and may be readily cleaned.

The inner face of the upper sash may also be 65 cleaned, and then by reversing the secondary frame the same operation may be gone through, and the upper sash, which is now in its reversed and lowermost position, may be cleaned on the outside, as well as both sides of 70 the upper hinged sash, and the outer face of the lower sliding sash, which is now in its reversed and uppermost position.

By my construction I gain several advantages over the old method of double windows. 75

First. The supplemental sash can be attached to or taken from the guided sash without much difficulty and without marring the appearance of the sliding sash, the only part remaining on the sliding sash being the pieces 7 80 of the hinge, and they being long and cylindrical present the appearance of beads. The lock 13 is unscrewed from the sliding sash and a plug inserted to fill up the hole in the sash. 85

Second. Both the swinging and sliding sash are operated together, and a perfect circulation of air is assured, and, third, the inner and outer surfaces of both sash can be easily cleaned without the necessity of removing the 90 secondary sashes.

Broadly speaking, my invention includes a supplemental sash hinged to a main sash, which in turn has a pivotal connection with the main frame, enabling it to be set in different inclined positions in the main frame, or, as in the present embodiment of my invention, the main sash may be reversed. 95

I do not limit myself to the manner of pivotally supporting the main sash in the main 100 frame nor to whether the supplemental sash is supported on the inner or outer side of the main sash, except as hereinafter noted in the claims. Again, while I have shown the swinging sash hinged at the sides of sliding sash I 105 do not limit myself in this respect.

Fig. 7 shows a pinion 21 journaled in the frame and engaging racks 22 on the sashes, whereby the sashes balance each other. 110

I claim as my invention—

1. In combination with a main frame, a secondary frame swinging in the main frame, a sash mounted therein, and a secondary sash hinged to the first-named sash, substantially as described. 115

2. In combination with a main frame, a secondary frame swinging in the main frame, sliding sashes carried by the secondary frame, and hinged sashes carried by the sliding sashes, substantially as described. 120

3. In combination, a main frame, a secondary frame swinging in the main frame, sliding sashes carried by the swinging frame, a hinged sash on the inner side of the lower sliding sash and a hinged sash on the outer side of the upper sliding sash, substantially as described. 125

4. In combination with a main frame, a secondary frame swinging therein, sliding sashes

carried by the secondary frame, supplemental sashes hinged to the sliding sashes, a packing interposed between each hinged sash and the sliding sash with which it is associated, substantially as described.

5. In combination with a main frame, a secondary frame swinging therein, sliding sashes carried by the secondary frame, supplemental sashes hinged to the sliding sashes and means 10 for operating the sashes in unison, substantially as described.

6. In combination with a main frame, a secondary frame swinging therein, sliding sashes carried by the secondary frame, supplemental 15 sashes hinged to the sliding sashes, racks on

the sliding sashes and a pinion connecting said racks, substantially as described.

7. In combination, with a main frame, a secondary frame swinging therein, sliding sashes carried by the secondary frame, supplemental 20 sashes secured to the sliding sashes, racks on the sliding sashes and a pinion connecting said racks.

In testimony whereof I affix my signature in presence of two witnesses.

EDMUND H. LUNKEN.
